UNITED STATES PATENT OFFICE.

CHARLES A. DEARBORN, OF NEW YORK, N. Y.

BLINDSTITCH SEWING MACHINE.

Application filed December 23, 1924. Serial No. 757,653.

The present invention relates to blind stitch sewing machines of the general type illustrated in my prior Patents No. 639,669, dated December 19th, 1899, and No. 814,025, dated March 6th, 1906.

The object of the present invention is to improve and modify this type of sewing machine to adapt it more especially for felling piped edges of seams. To this end the looper movement has been modified to carry a second thread and produce in combination with the needle thread a double chain stitch. The looper operating means have been improved to cause the looper to move forwardly above the needle and presser foot on one side of the line of stitches, and backwardly below the needle on the same side of the line of stitches, and to turn 90° at the ends of its forward and backward strokes. The presser foot has in the past usually been a single rigidly supported member against which the work is pressed by a yielding work support. In the new machine the presser foot is divided, the main part at the left of the ridge forming rib above the work support being fixed, while the auxiliary part at the right of the ridge forming rib is mounted upon a spring supported arm to yield laterally away from the line of stitching under the strain of an extra heavy part of the work such as is encountered with heavy cross seams.

In order that the invention may be fully understood it will first be described with reference to the accompanying drawings and afterwards pointed out more particularly in the annexed claims:

In said drawings:

Fig. 1 is a side elevation of the improved blind stitch felling machine;

Fig. 2 is a plan view of the same with the sewing machine arm, the needle shaft, and other parts broken away for the sake of clearness;

Fig. 3 is a detail front elevation of the stitch forming mechanism, showing also the work supporting mechanism in section;

Fig. 3^a is a detail side elevation of parts shown in Fig. 3;

Fig. 4 is a detail view similar to Fig. 3, showing the needle in its retracted position;

Fig. 5 is a vertical longitudinal sectional view taken on the line 5—5 of Fig. 3;

Fig. 6 is a detail horizontal sectional view taken on the line 6—6 of Fig. 1;

Fig. 7 is a detail transverse sectional view taken on the line 7—7 of Fig. 1;

Fig. 8 is a detail side elevation of the looper movement showing the looper nearing its rearmost position;

60

Fig. 9 is a detail plan view of the looper and needle in the same position as Fig. 8;

Fig. 10 is a plan view of the looper movement showing the looper withdrawn to its extreme rear position;

65

Fig. 11 is a detail side view of the needle and looper in the position illustrated in Fig. 10;

Fig. 12 is a view similar to Fig. 8 showing the looper starting on its forward motion;

70

Fig. 13 is a detail plan view of the needle and looper in the position of Fig. 12;

Fig. 14 is a plan view similar to Fig. 10 showing the looper in its extreme forward position; and

75

Fig. 15 is a detail view illustrating the relation of the needle and looper corresponding with the position shown in Fig. 14.

1 is the main frame of a sewing machine 80 of the type set forth in my above named patents and 2 is the sewing machine arm projecting forwardly from the main bearing 3 to a point above and adjacent to a work support presently to be referred to. 85 The frame 1 has an upwardly presented rigid arm 5 in which is rigidly mounted the horizontal bolt 6 upon which is journalled a rocking frame 7, which projects rearwardly and forms a U-shaped yoke carrying the ridge forming disk 10 journalled in it at 11 and the independently yielding working supporting plates 12 pivoted at 13 upon arms 14 journalled at 15 and controlled by springs 16.

95 The U-shaped frame 7 has a downwardly projecting arm 20 connected at 21 by a strong contractile spring 22 attached at its inner end to a flange 23 of the machine frame 1.

An adjusting screw 25 is threaded in lugs 26 of the machine frame and engages at its forward end with the arm 20 and is provided at its rear end with a milled hand operated head 27 by which the screw can 105 be adjusted. The head 27 has a bevelled face 28 marked off in a suitable scale to indicate at a glance the adjusted position of the screw 25. Adjacent to the head 27 is a

110 grooved cylindrical portion 29 with which

engages a spring detent 30 mounted upon a pin 31 of the machine frame and serving to hold the adjusting screw 25 against accidental displacement. A second screw 33 is 5 adjustably mounted in the lug 26 in the path of the arm 20 to limit the movement of the arm in one direction under the action of the spring 22.

35 is the main fixed portion of the presser 10 foot secured to the lower end of a plate 36 which is adjustably mounted on a vertical face of the machine arm 2 by means of machine screws 37. This fixed portion of the presser foot is mounted above the work support 15 to the left of the ridge forming rib and carries additional elements hereinafter referred to.

66 is a shoe formed on the lower end of plate 67 secured to a vertical face of machine 20 arm 2 by screws 68. The shoe 66 is fixed in the horizontal plane of the presser foot alongside of the reciprocating feed dog 70, hereinafter referred to, and serves to confine the work downwardly adjacent to the feed.

25 40 is the auxiliary laterally adjustable portion of the presser foot consisting of a short forwardly presented blade mounted upon the lower end of a curved lever 41 pivoted to the sewing machine arm by means of 30 a screw 42 and having an arm 43 projecting to the left above a limiting stop 44, which confines the extent of movement of the auxiliary presser foot member away from the fixed member. A contractile spring 45 en-

35 gages the arm 43 and connects with an arm 46 upon the machine frame for giving the presser foot member 40 a spring tendency to move inwardly toward the vertical plane of the ridge forming disc 10. This spring

40 motion of the auxiliary presser foot is limited by a conical adjusting screw 50 threaded in the machine arm and engaging arm 43 of lever 41. From this structure it will be observed that this auxiliary portion 40 of 45 the presser foot is free to yield outwardly against the action of spring 45 up to the limit of stop 44. Laterally yielding member 40 is presented directly in front of feed dog 70 and above the right-hand work supporting plate 12. Member 40 cooperates with fixed shoe 66 in resisting upward pressure of the work passing over the work support.

60 60 is the curved needle carried by the arm 61 adjustably mounted upon the needle rock 55 shaft 62 driven by the rock arm 63, the universal joint link 64 and eccentric on the main drive shaft 65 in the same manner as previously employed in this type of machine. The needle reciprocates in guide 60 grooves formed in the concave upper faces of the main and auxiliary portions of the presser foot 35 and 40.

70 is the two part reciprocating upper feed secured by screws 71 to the forward 65 projection of the oscillating reciprocating

feed bar 75 which is driven at its rear end by eccentric connection 76 with the main shaft of the machine and supported between its ends by a headed guide pin 77 projecting laterally from a lug of the machine arm and 70 adjustably secured therein by set screw 78. This pin 77 passes through a slot in the feed bar 75 and confines it to its vertical plane of operation. The feed bar 75 has a universal joint 80 with a link 81 which in 75 turn has a universal joint 82 with a rock arm 83 adjustably mounted upon the needle rock shaft 62 by means of set screw 84.

90 is the looper proper adjustably mounted in the forward end of a cylindrical looper 80 bar 91 which is secured at its rear end to a yoke 92 trunnioned upon an eccentric lug 93 of a bearing sleeve 94, which is journalled upon an angularly set crank pin 95 of the crank disk 96 carried by the main shaft 65 of 85 the machine. This angularly set crank with universal joint connection with the looper rod is similar to that shown in my above named patents and forms part of the present invention excepting only as an essential 90 part of the mechanism for operating the looper in the manner hereinafter described.

The looper bar 91 passes freely through aligned bearing sleeves 100 of a floating bearing frame 101 which is formed at its 95 forward end with a bearing yoke 102 freely pivoted at 103 upon the lower end of a vertical pivot pin 105, which turns freely in bearing opening 106 formed eccentrically in the cylindrical bearing block 107 which is 100 mounted adjustably in the split socket 108 of the sewing machine arm. This bearing block 107 is formed with a squared upper end by which it can be turned in the split socket of the machine frame and secured in the desired 105 adjusted position by the set screw 110. By adjusting the block 107 the vertical pivot pin 105 can be shifted laterally and forwardly and backwardly for accurately positioning the point of the looper to cause it to properly cooperate with the needle. The pivot pin 105 is confined in the bearing block 107 by means of the headed set screw 109 threaded in the upper end of pin 105 and engaging the upper end of bearing block 107.

One of the important accomplishments in modifying this type of blind stitch sewing machines to adapt it specially for felling heavy seams is the reduction in the throw of the looper from the lower plane of its backward stroke to the upper plane of its forward stroke. The distance between these two planes of movement of the looper is barely more than the thickness of the needle. This slight vertical throw between the two 125 planes of movement of the looper is accomplished by mounting the pivot pin 105 of floating bearing frame 101 as far forward in the machine frame as is possible. It will be noted that the pivot 103 of said floating 130

bearing frame 101 is just back of the transverse path of the needle. This looper movement is important also because it places the looper in its forward position above the path 5 of the needle with the eye of the looper extending horizontally above the fixed portion of the presser foot conveniently for threading the looper.

The main fixed portion 35 of the presser 10 foot is provided with an upstanding rib 120 upon its inner edge in which is formed a needle receiving recess or groove 121 corresponding in position with the transverse groove 122 in the upper face of foot member 35. A deep longitudinal groove 125 is formed in foot member 35 for the operation 15 of the looper 90.

130 is a cloth engaging member pivoted in the slotted forward end of presser foot 20 35 and engaged by a spring 131 for holding its cloth engaging downwardly presented end 130^a alongside of the ridge forming disc 10.

When the work is placed in the machine, 25 the work support is depressed usually by a foot pedal (not shown) connected with U-shaped frame 7 and the work inserted between the supporting plates 12 and the two part presser foot, the heavy or hemmed portion 30 of the work being presented at the right of the ridge forming disk beneath the laterally yielding foot member 40. The edge of the seam, which is commonly piped, is presented over the ridge forming disk 10 and 35 the work at the left is pressed downwardly by the spring pressed plate or dog 130 to confine the work as closely as possible upon the disk 10 to thereby maintain the line of stitches closely beneath the piped edge of 40 the seam. The upstanding rib 120 diverts the piped edge of the seam slightly toward the disk 10 to hold it out of the way of the top feed member which engages the work parallel with the longitudinal groove 125.

45 The threading of the needle and looper is indicated in the drawings and the cooperation of the needle and looper in forming a double thread chain stitch will be fully understood from Figs. 8 to 15 of the drawings. Starting the looper and needle in the 50 position shown in Figs. 10 and 11 with the needle penetrating the work and the looper in its extreme rearward position, the looper moves forward in its upper plane above the needle, taking the loop from the needle as the needle is withdrawn from the work, the feed dog feeding the work one stroke over the work support. In completing the forward movement of the looper and the retraction 55 of the needle, the looper passes through the position shown in Fig. 12 into the position shown in Fig. 14. The final movement of the looper is from the position shown in Fig. 14 to that shown in Fig. 8, 60 which movement withdraws the looper rear-

wardly in its lower plane beneath the path of the needle, while the needle again penetrates the work above the disk 10 and takes the upstanding loop from the point of the looper. This cycle of movements is repeated 70 for each stitch. All of the movements of the looper are performed on one side of the line of stitching,—that is to the left of the vertical plane of the ridge forming disk looking at the front of the machine. The 75 looper movement of my present invention is clearly distinguishable in this characteristic from the machine of my above named Patent No. 639,669, in which the looper oscillated back and forth from one side to the 80 other of the line of stitching.

The inclined crank pin yoked to the end of the looper rod causes the looper to oscillate back and forth 90° as it reciprocates across the path of the needle. This quarter 85 turn of the looper is made for several reasons. In the first place, it turns so as to present the eye of the looper horizontally above the presser foot in convenient position for threading the looper. It would be 90 practically impossible to thread the looper unless it were turned in this way. This turning of the looper is further important in presenting the looper with its narrowest dimension above the needle as the looper takes the loop from the needle and with its thicker dimension below the path of the needle as the needle takes the loop from the looper. In this latter position the looper 95 thread is held firmly and given substantial lateral support in the path of the needle by the walls of the looper eye because of the thickness of metal of the looper at the eye.

The improved work handling mechanism (including the divided presser foot, the feed and other associated features above described), as distinguished from the stitch forming mechanism of the present application, is claimed in my divisional application Serial No. 45,292, filed July 22, 1925. 100 110

I claim:

1. In a sewing machine having a work support, a presser foot and work feeding means, the combination of a reciprocating needle, and a looper operating above the work support and presser foot and cooperating with said needle, with looper operating means adapted to cause said looper to move forwardly above the needle on one side of the line of stitches and backwardly below the needle on the same side of the line of stitches, and to turn 90° at the ends of its forward and backward strokes. 115 120

2. In a sewing machine having a work support, a presser foot and work feeding means, the combination of a reciprocating needle, and a looper formed with a thread carrying eye cooperating with said needle, with looper operating means comprising a 125 yoke attached to the looper, an angularly 130

set driving crank, and universal joint connection between said yoke and driving crank arranged to impart reciprocating movements across the path of the needle and a 5 quarter turn between reciprocating movements.

3. In a sewing machine having a work support, a presser foot and work feeding means, the combination of a reciprocating 10 needle, and a looper operating above the work support and presser foot and cooperating with said needle, a floating frame having looper bearings and universal joint support adjacent to the path of the needle, and 15 looper operating means adapted to cause said looper to move forwardly above the needle on one side of the line of stitches and backwardly below the needle on the same side of the line of stitches, and to turn 20 90° at the ends of its forward and backward strokes.

4. In a sewing machine having a work support, a presser foot and work feeding means, the combination of a reciprocating 25 needle, and a looper movable forwardly and backwardly across the path of the needle, with a floating frame having looper supporting bearing and universal joint support adjacent to the path of the needle, 30 causing the looper to operate on one side only of the line of stitches.

5. In a sewing machine having a work support, a presser foot and work feeding 35 means, the combination of a reciprocating needle, and a looper movable forwardly and backwardly across the path of the needle, with a floating frame formed with aligned 40 looper bearings and horizontal and vertical pivot supports at one end of said frame adjacent to the path of the needle and above said aligned bearings.

6. In a sewing machine having a frame, a work support, a presser foot and work feeding means, the combination of a reciprocating 45 needle, and a looper movable forwardly and backwardly above and below the path of the needle, with a floating bear-

ing frame formed with aligned looper bearings and a horizontal pivot bearing at one end of said frame above said aligned bearings, and a vertical pivot pin journaled in the machine frame and pivotally connected with said horizontal pivot bearing. 50

7. In a sewing machine having a frame, a work support, a presser foot and work feeding means, the combination of a stitch forming needle, and a looper reciprocating across the path of the needle, with a floating looper bearing frame, a vertical pivot pin having horizontal pivot connection with one 60 end of said bearing frame, and a vertical bearing block adjustably mounted in the machine frame, said bearing block having an eccentric bearing opening in which said vertical pivot pin is journaled. 65

8. In a sewing machine having a frame, a work support, a presser foot and work feeding means, the combination of a stitch forming needle, and a looper reciprocating across the path of the needle, with a floating looper bearing frame formed at its forward end 70 with a horizontal bearing yoke, a vertical pivot pin, a horizontal pivot pin connecting said yoke and said vertical pivot pin, a vertical bearing block adjustably mounted in the machine frame and having an eccentric bearing opening in which said vertical pivot pin is journaled. 75

9. In a sewing machine having a work support, a presser foot and work feeding 80 means, the combination of a stitch forming needle, and a looper mounted upon a looper rod and movable forwardly and backwardly across the path of the needle, with a floating looper-bearing frame having universal joint 85 support at its end adjacent to the path of the needle to cause the looper to operate on one side only of the line of stitches, and looper driving mechanism comprising a yoke secured to the looper rod, a bearing sleeve 90 jointed to said yoke, and an angularly set driving crank upon which said sleeve is journaled.

CHARLES A. DEARBORN.
